UNITED STATES PATENT OFFICE.

AMAND PLANT, OF NEW YORK, N. Y.

DESIGN FOR A SHIRT-BOSOM.

SPECIFICATION forming part of Design No. 11,980, dated October 19, 1880.

Application filed August 19, 1880. Term of patent 3½ years.

To all whom it may concern:

Be it known that I, AMAND PLANT, of the city, county, and State of New York, have invented a new and original Design for Shirt-Bosoms, of which the following is a full, clear, and exact description, reference being had to the accompanying drawing, making part of this specification, which represents a front elevation of my improved shirt-bosom.

10 This invention has reference to an improved design for a campaign shirt-bosom of neat and a striking configuration; and it consists of a shield-shaped bosom part provided with a medallion upon its lower part and with curved and tapering shoulder-extensions at its upper part, and of overlapping collar-sections applied to the inner edges of the shoulder-extensions.

20 In the drawing, A represents the body or main portion of my improved shirt-bosom, which is of shield shape, and provided with a medallion, B, of round, oval, or other shape, upon which the pictures of the presidential candidates of either party or other campaign 25 insignia are printed. The main portion A is

constructed above the medallion, and then extended in upward direction, so as to form two curved and tapering shoulder-pieces or yokes, C. To the inner edge of each shoulder-piece or yoke C is applied an overlapping collar-section, D. The outer edges of the shoulder-pieces C, main portion A, and medallion B are finished off by stitchings, trimmings, or braids, by which a new and ornamental appearance is imparted to the shirt-bosom.

35

Having thus described my invention, I claim as new and desire to secure by Letters Patent—

The design for a shirt-bosom, consisting of a shield-shaped body or main portion, A, medallion B, curved and tapering shoulder-pieces C, and overlapping collar-sections D, substantially as shown and described.

40 In testimony that I claim the foregoing as my invention I have signed it this 16th day 45 of August, 1880.

AMAND PLANT.
